COIL CAP COVER

Stanley E. Estes, 543 W. 184th St.,
Gardena, Calif. 90247

Filed Feb. 5, 1970, Ser. No. 21,274

Term of patent 14 years

Int. Cl. D13—02

U.S. Cl. D26—5

FIG.1

FIG.2

FIG.3

FIG.4

FIG.5

FIG. 1 is a perspective view of a coil cap cover showing my new design;

FIG. 2 is an elevational front view of the coil cap cover shown in FIG. 1;

FIG. 3 is an elevational side view of the coil cap cover shown in FIG. 1;

FIG. 4 is a top plan view of the coil cap cover shown in FIG. 1; and

FIG. 5 is a bottom plan view of the coil cap cover shown in FIG. 1.

I claim:

The ornamental design for a coil cap cover, substantially as shown.
